FIG. 1

Patented Jan. 18, 1921.

FIG. 2

FIG. 3.

FIG. 4

David W. Sjoholm Inventor

Chamberlain & Newman Attorneys

UNITED STATES PATENT OFFICE.

DAVID W. SJOHOLM, OF BRIDGEPORT, CONNECTICUT.

PUNCH-HOLDER.

1,365,738.

Specification of Letters Patent. Patented Jan. 18, 1921.

Application filed May 29, 1920. Serial No. 385,172.

To all whom it may concern:

Be it known that I, DAVID W. SJOHOLM, a citizen of the United States, and resident of Bridgeport, in the county of Fairfield 5 and State of Connecticut, have invented certain new and useful Improvements in Punch-Holders, of which the following is a specification.

This invention relates to punch holders such as are used in connection with a power press and employed for sheet metal punching.

The object of the invention is to provide a novel form of punch holder to be carried by the reciprocating head of a power press whereby a tool may be readily supported for operating purposes, and particularly to provide means whereby the punch will be normally carried loose in the holder so as 20 to first strike lightly on the work to mark the same, and further to provide hand operating means whereby the same punch may be secured in the holder for effective punching operations.

In the embodiment of my invention I employ a special form of sleeve or holder in which the punch is removably supported, said sleeve being fitted to the reciprocatory head or other movable part of the press, 30 and in connection with the sleeve I provide a slide which when positioned in the sleeve serves to support the punch for punching operations, the sleeve is normally disengaged and adapted to be hand-operated for holding the punch in position.

With these and other objects in view the invention resides and consists in the construction and novel combination and arrangement of parts hereinafter more fully 40 described, illustrated in the accompanying drawings, and pointed out in the claims hereto appended, it being understood that various changes in the form, proportion, size and minor details of construction within 45 the scope of the claims may be resorted to without departure from the spirit or sacrificing any of the advantages of the invention.

Similar characters of reference denote 50 like or corresponding parts throughout the several figures of the accompanying drawings forming a part of this specification, and upon which,

Figure 1 shows a front elevation of my 55 improved form of punch holder as ap-

plied to the lower portion of the head of a press.

Fig. 2 is a detached front elevation of the sleeve shown in the head illustrated in Fig. 1.

Fig. 3 is a horizontal cross sectional view taken on line 3—3 of Fig. 1, and

Fig. 4 is a vertical sectional view taken on line 4 of Fig. 1.

Referring in detail to the characters of reference marked upon the drawings, 6 indicates a carrier which in practice would be made in two parts and secured together by bolts 7. The carrier is secured to the reciprocating head of a press, not shown, and 70 which may be of any preferred construction. This carrier is provided with a central hole 8 having an annular enlargement 9 around its upper end portion to receive the holder 10 which is of a general cylindrical shape 75 having the outwardly disposed flanges 11 upon the upper end portion that is seated in the said enlargement 9 in the carrier. An annular enlargement 12 on the lower end of the holder forms an annular shoulder 13 80 that is seated against the underside of the carrier. The holder further includes a longitudinal hole 14 having a contracted lower end 15 forming an annular shoulder 16 to support the annular flange 17 around the 85 top of the punch 18. A side opening 19 with opposite grooves 20—20 are formed in the front side of the holder to permit the punch to be introduced from the front side and to then be dropped down in position so that 90 the flange 17 will rest upon the shoulder 16 of the holder.

A filling piece 21 is slidably fitted in the longitudinal bore 14 and rests upon the head of the punch and is free to move vertically 95 in the holder with the punch, when the slide 22 is held out of engagement as indicated by dotted lines in Fig. 4. In this connection it will be seen that the punch can only be inserted or removed when the slide is out 100 and the filling block carried above the parallel grooves 20 in the holder.

The slide 22 is positioned to be operated at a right angle to the filling block and punch and when shoved in becomes positioned above the filling block in a manner to hold the same and the punch down in position for effective operations. The slide is fitted in suitable ways of the carrier and holder and is provided with stops 23 to limit 110

its outward movement. The slide is normally held in its outward position by means of the spring 24 positioned in the longitudinal bore 25 of the slide and having one end seated against the closure plug 28 and the other end engaging the bearing piece 27 slidably mounted in the slots 26-26 formed in the opposite sides of the slide mounted in the slots and having its two ends shouldered 10 against the face of the carrier.

When the slide is extended its inner end is free and clear of the spacer block so that the same and its punch will be free to rise in the holder when the punch comes in contact with the work by the vertical reciprocation of the head, and will likewise promptly slide back to their normal resting place when the head of the machine is raised.

From the foregoing it will be seen that 20 with the slide in this position a light operation of the point of the punch will be had upon the stock if placed beneath the punch, which will be sufficient to mark the metal so that the operator can determine if the metal 25 is properly placed beneath the punch for a punching operation, and when found to be properly positioned, the slide would be shoved in over the top of the block while the head is in its raised position, thus locking 30 the punch and causing it to enter the metal with the next stroke of the press.

Having thus described my invention, what I claim and desire to secure by Letters Patent is—

1. In a punch holder, the combination 35 with a reciprocating carrier, of a holder mounted therein having a longitudinal bore and means for supporting a punch therein, a punch mounted therein, a spacer block resting upon and adapted to reciprocate 40 with the punch in the holder, a slide fitted in the holder and adapted to engage the block to secure the punch in position, and means to normally hold the slide in a disengaged position.

2. In a punch holder, the combination 45 with a reciprocating carrier, of a holder mounted therein having a longitudinal bore and an opening in its side to receive the punch, a spacer block loosely mounted in the holder above the punch, a slide adapted to be manually operated to engage the block and lock the punch, and spring means to normally hold the slide out of engagement.

Signed at Bridgeport in the county of 55 Fairfield and State of Connecticut this 27th day of May, A. D., 1920.

DAVID W. SJOHOLM.
